UNITED STATES PATENT OFFICE.

JOHN J. SEMASHKO, OF MORRISVILLE, PENNSYLVANIA.

TILE-RECEIVING MACHINE.

Application filed August 18, 1926. Serial No. 130,088.

This invention has reference to a machine for handling tiles, such as are used on floors and the like in bath rooms and other places and has for its primary object to simplify 5 and generally improve the construction of the tile receiving machine upon which I, on January 23, 1926, applied for U. S. patent protection, the said application bearing the Serial No. 83,278.

10 To the attainment of the foregoing and other objects which will present themselves as the nature of the invention is more fully disclosed, the improvement resides in the construction, combination, and operative association of parts, one satisfactory embodiment of which is disclosed by the accompanying drawings.

In the drawings:

Figure 1 is a top plan view of my improvement.

Figure 2 is a sectional view on the line 2—2 of Figure 1.

Figure 3 is a sectional view on the line 3—3 of Figure 2.

25 Figure 4 is a sectional view on the line 4—4 of Figure 2.

Figure 5 is a sectional view approximately on the line 5—5 of Figure 2.

Figure 6 is an enlarged detail sectional 30 view approximately on the line 6—6 of Figure 5.

Figure 7 is a sectional view approximately on the line 7—7 of Figure 2.

Figure 8 is a fragmentary top plan view 35 with the machine provided with the means for bunching round or square tiles on the board or tray toward each other.

Figure 9 is a sectional view approximately on the line 9—9 of Figure 8.

40 Figure 10 is a perspective view of the guide plate for the carriage.

Figure 11 is a front elevation of the gauge plate.

Referring now to the drawings in detail, 45 the numeral 1 designates a frame which is preferably constructed of angle irons. This frame is placed adjacent to a tile forming machine. The frame 1, adjacent to its top, has horizontal rails 2 that provide a track 50 for the wheels 3 of a carriage 4. The carriage has its flat top arranged in a line with the outlet for tiles that have been molded in a tile making machine or press. The tile making machine or press is disclosed by the

dotted lines in Figures 1 and 2 of the drawings, and is indicated by the numeral 5. Fixed to the plunger of the machine 5 and extending outwardly therefrom in the direction but over the frame 1, there is a pair of spaced horizontally disposed rods 6. 60 These rods 6 are connected with a transverse member 7 that has fixed to and depending from its corners bars 8, the lower ends of the said bars being connected by a transverse member 9. Adjustably secured on each of the bars 8 by means 10, there is a socket member 11, and journaled between the bars 8 in the said socket 11 there is a shaft 12. Journaled on the shaft 12, adjacent to each socket or bearing member 11, and held 70 from longitudinal movement on the said shaft 12, there are links 13. The shaft 12, at points equidistant from the center thereof, is formed with enlargements 14 that receive therebetween and hold from lateral 75 movement with respect to the shaft, a plate 15 whose lower end is secured to the connecting element 9 for the rods. The plate 15 has secured thereon a finger 16 that is directed toward the frame 1. 80

Pivoted on the frame there is a pair of bell crank levers 17, one arm of each of these levers being pivotally connected to one of the links 13 and the second arm of each lever being pivotally connected to a link 85 18. The links 18 are adjustably pivoted each to a lever 19, and the lower end of each lever 19 is fixedly secured upon a shaft 20 arranged transversely with respect to the frame 1 and journaled in suitable bearings 90 on the said frame. The upper end of each lever 19 is slotted, as at 21, and passing through these slots there are pins 22 that are received in depending brackets 23 on the carriage 4. 95

As far as the description has progressed it will be noted that the movement of the plunger of the machine 5 will impart a like movement to the movable frame so that the latter will turn the bell crank levers to 100 swing the levers 19 to move the carriage 4 either toward or away from the machine 5. Thus it will be noted that the reciprocation of the plunger will cause the carriage to alternately move into tile receiving position and away from the machine or press. 105

The improvement contemplates the employment of an elevator, the same including

2 a vertically disposed standard 24 that is guided through suitable bearings 25 on the frame 1 and which has on its upper end a flat head 26. The standard 24 is notched 6 longitudinally for a considerable distance on one of its faces, and in this notch there is removably secured a rack bar 27. Connected to a bracket on the standard there is one 10 end of a flexible element 28, the same being trained over a sheave wheel 29 whose shaft is suitably journaled on the frame, and the end of the upper lead of the flexible element 28 is secured to a weight 30. The weight 30 is of cylindrical formation and is 15 received in a tubular member 32. Passing through the weight 30 there is a pipe or tube 33 on whose upper end there is fixed a cock 34. The weight and the tube provide the elevator with a buffer of the dash-pot type, 20 but the weight is also designed to move the elevator to raised position. To insure a constant or steady movement of the elevator the cock is regulated to permit air flowing from the cylindrical member or pot 32 25 through the weight 34. The standard 24 has fixed on its lower end a laterally extending foot piece 35.

Designed to rest on the top 26 of the elevator there is a tile receiving board or 30 tray 36. This tray has its sides and its end directed toward or away from the frame provided with depending cleats 37, and these cleats and the side plates contacting the sides of the head 26 hold the tray properly positioned on the elevator.

The carriage 4 has on its flat upper face 35 longitudinally extending ribs 38 and these ribs are designed to pass through transverse notches 39 on the under face of a guide plate 40 whose ends are fixed on the frame directly above the carriage.

Vertically arranged and mounted for slide- 45 able movement on one end of the frame 1 there is what I will term a feed bar 41. On the face of the feed bar, adjacent to the machine 5 there is fixed a substantially L-shaped bracket 42. The outwardly extending arms of the bracket 42 are threaded and screwed therethrough there are bolt mem- 50 bers 43 and 44 respectively. Lock nuts 45 and 46 engage the bolts and hold the same adjusted on the bracket. The finger 16 on the slideable frame is arranged between the bolts 43 and 44, so that considerable lost motion will be provided in the vertical move- 55 ment of the said slideable frame in both directions before the bolts are contacted by the frame in the raising or lowering of the feed bar.

60 The bracket 42 may have angle sides be- 65 tween which there is fixed the socket or hous- ing 47 for a spring influenced dog 48, the latter engaging with one of the teeth of the rack bar 27. The lower bearing through

formed with an angle extension on which is fixed the socket or housing 49 for a spring influenced holding dog 50 that also engages with one of the teeth of the rack bar 27.

The elevator is raised so that the tray 37 is in a position to receive thereon the first series of tiles which have been molded in the machine. After this series of tiles have been formed the plunger of the ma- 70 chine will be elevated which will cause the slideable frame to be moved upwardly so that the bell crank levers 17 and the levers 19 will be swung to move the carriage 4 in a position to receive the said tiles from the machine. The tiles are directed through the machine into the ways between the ribs 38 on the carriage 4. As additional material is fed into the machine and the plunger de- 75 scends the slideable frame 8 will be moved downwardly and the carriage will be moved to the position illustrated in Figure 2 of the drawings. The tiles will contact with what I have termed the guide bar 40 which will move the same from off of the carriage onto the tray 37. The downward movement of the plunger of the machine will cause the finger 16 to contact with the lower adjustable stop bolt, thus moving the feed bar downwardly and causing the operating dog 48 to likewise move the elevator downwardly a distance equal to the distance between two of the teeth on the rack bar and this distance also equals the thickness of the tiles which have been deposited on the tray 36. 80 The holding dog prevents the upward movement of the elevator, but the actuating dog 48 is free to move with the feed bar when the latter has its adjustable stop bolt 43 contacted by the finger 16 on the movable frame when the plunger of the machine 5 is raised as will, it is thought, be perfectly 85 apparent.

On certain of the aligning transverse brace members for the frame 1 there are fixed 90 spaced longitudinally extending angle irons 51. Journaled in suitable bearings centrally of the angle irons 51 there are sprocket wheels around which there is trained an endless sprocket chain 52. This chain has out- 95 standing lugs or fingers 53. The shaft of one of the sprocket wheels 52 has fixed thereon a pulley 54, and this pulley has arranged therearound a belt connected to a suitable 100 source of power so that the chain is con- 105 stantly revolved in one direction. Thus the upper lead of the chain is caused to move on the frame in a direction away from the machine 5. When series of tiles of a desired 110 number have been stacked on the tray 36, 115 in a manner as above described, the elevator will be lowered so that one of the fingers 53 of the endless chain will contact with the outer cleat 37 of the said tray, thus moving 120 the tray and the stacked tiles off of the ele- 125 130

vator and outwardly on the frame to a position to be removed from the frame. Thereafter another tray 36 is arranged on the head 26 of the elevator and the latter is raised to its uppermost position. In instances where a sufficient number of tiles has not been cast in the machine 5 to lower the elevator a sufficient distance to cause the tray to be engaged by the belt of the endless chain as above described, the operator will press his foot on the foot piece 35 of the said elevator and thereby manually lower the same to a position whereby the tray will be removed from the top of the elevator and moved over the guide wheels 51 by the endless chain.

Because of the engagement of the dogs with the teeth of the rack bar 27 the weight 37 cannot influence the elevator to its upper position. Therefore, I provide a dog release. The dog release includes a flat plate or bar 54 that has its upper end provided with an elongated slot to receive therethrough a pin 55 secured to a bracket 56 that depends from the frame. The bar 54 is influenced in an upward direction through the medium of a spring 57. The bar passes through openings in the sockets or housings 47 or 49 for the dogs 48 and 50 and also through openings in the said dogs. The bar 54 is provided with angle notches 58 that receive therein and limit the outward movement of the spring influenced dogs. To the lower end of the bar 54 there is secured a rod or like element 59 which is loosely connected to a pivotally supported foot pedal 60. Obviously weight upon the foot pedal 60 will cause a downward movement of the bar 54 and the angle walls provided by the notches will be brought against the dogs to move the same out of rack bar engagement and into their housings. The weight 30 will then act to elevate the elevator.

When round or square tiles are received on the carriage they are spaced away from each other the same distance as the ribs and hexagonal tiles and in this instance it is not necessary to provide the carriage with the ribs 38, but obviously it is desirable that the tiles be bunched so that the superimposed series will properly rest upon the tray 36. To accomplish this the carriage 4 may have at one of its ends an upwardly directed spring influenced dog catch 61 and pivoted on what I have termed the guide bar or plate 40 there is a lever 62. The lever is influenced by a spring 63 to one position and the end of the lever nearest the dog 61 is widened and formed with an angle edge 64. The second end of the lever has pivotally secured thereto, as at 65, a rocker member which I will term a pusher arm and which is indicated by the numeral 66. When the carriage moves forward the same will ride

beneath the widened end of the lever and thereafter will spring outwardly so as to contact with the inner edge of the said lever 62. The return movement of the carriage will cause the dog to ride over the angle edge or surface 64 of the lever so as to swing the same angularly as disclosed by dotted lines in Figure 8 of the drawings. This also moves the pusher arm 66 inwardly so that the tile which has been swept off of the carriage by what I have termed the guide plate or bar 40, onto the tray 36, will be bunched together on said tray.

In order to remove all dust from the tiles received on the tray I provide an electrically driven fan 67 (see Figure 1). This permits of the series of tiles received on the said tray properly resting one on the other.

The tiles molded in the machine 5 may slightly vary in thickness which will not permit of the same being properly stacked with our tile receiving machine. Therefore, I provide a gauge means whereby the operator of the machine will have ample knowledge of the quantity of the material to be fed thereinto. This gauge provides a pair of arms 68 which project outwardly from the upper member of the slideable or reciprocatory frame that carries the finger 16. A cross member 69 connects the outer ends of the arms 68, and passing through openings in the cross member there are bolts or like elements 70 whose lower or outer ends are fixed on a guide plate 71. Surrounding each bolt and contacting with the guide plate 71 there is a helical spring 72. One end of the guide plate is flanged upwardly and from thence extended outwardly, as at 73. Pivotally supported on the top, adjacent one end of the plate 40, there is an arm 74 that is influenced in an upward direction through the medium of a spring 75. This arm 74 underlies and contacts with the part 73 of the gauge plate 71 or if desired with a lug on the said part 73. The arm 74 also passes through a slot 76 in a gauge plate 77. When the arm is in the center of the gauge plate the tile is being manufactured the desired thickness, but when the said arm swings either upwardly or downwardly beyond the center the tile is being manufactured at undesired thicknesses. By this arrangement the operator of the machine 5 has visible knowledge of the precise amount of material to be inserted in the machine for manufacturing the tiles all of the same thicknesses.

Manifestly the gauge plate 71 contacting with the tile deposited on the tray will serve to sustain the series of tiles in proper alignment, and rack bars 27 having teeth of different lengths will be employed when the machine is used in connection with tiles of different thicknesses.

It will be seen from the foregoing de-

scription when read in connection with the accompanying drawings that I have materially simplified and improved the tile receiving machine construction set forth in my 5 copending application Serial No. 83,278, filed January 23, 1926. It is also thought that the foregoing description will clearly set forth the advantages and novel features of my invention but it is desired to be understood that I do not desire to be restricted to the precise details herein set forth and hold myself entitled to all such changes therefrom as fairly fall within the scope of what I claim.

10 15 Having described the invention, I claim:—

1. A machine for the purpose set forth comprising an elevator, a weight for influencing the elevator in an upward direction, a cylinder in which the weight is guided, a 20 valve controlled air port in the weight, a tile receiving tray on the elevator, a carriage movable over the elevator, a guide for the carriage, designed to wipe tile off of said carriage onto the tray, means for imparting a reciprocatory movement to the carriage, means for lowering the elevator a predetermined distance when the carriage is moved to discharge position, and means including a 25 endless conveyor for removing the tray

from the carriage when the elevator has 30 been lowered a predetermined distance.

2. A machine for the purpose set forth, comprising an elevator, a tile receiving tray resting on the top of the elevator, a removable rack bar associated with the elevator, a feed bar, a spring influenced dog carried thereby to engage the rack, a spring influenced holding dog for the rack, a weight influencing the elevator in an upward direction, a cylinder in which the weight is 40 guided, said weight having a valve controlled air port therethrough, a wheeled carriage movable over the elevator, a guide for the carriage designed to wipe tile off of said carriage onto the tray, means for reciprocating the carriage and said means operable to impart a reciprocatory motion to the feed bar for lowering the elevator a predetermined distance after the carriage has passed thereover, means for drawing the tray off of the elevator when the said elevator has been lowered to a predetermined position and means for simultaneously releasing the actuating and holding dogs for permitting the weight to return the elevator to initial 55 uppermost position.

In testimony whereof I affix my signature.

JOHN J. SEMASHKO.
